UNITED STATES PATENT OFFICE.

WILLIAM F. REMPPIS, OF READING, PENNSYLVANIA, ASSIGNOR TO THE READING STANDARD MANUFACTURING COMPANY, OF SAME PLACE.

DESIGN FOR A CROWN FOR BICYCLE-FORKS.

SPECIFICATION forming part of Design No. 31,563, dated September 26, 1899.

Application filed August 22, 1899. Serial No. 728,128. Term of patent 7 years.

To all whom it may concern:

Be it known that I, WILLIAM F. REMPPIS, a citizen of the United States of America, and a resident of Reading, in the county of Berks and State of Pennsylvania, have invented and produced a certain new and original Design for a Crown for Bicycle-Forks, of which the following is a specification.

Figure 1 is a side elevation of a fork-crown, showing my design. Fig. 2 is a plan view of the same.

As shown in the drawings, the leading feature of my design consists of a series of parallel uniformly-spaced bent truss-plates $a b c$, each having its central steering-tube-connecting portion a' , b' , or c' set in a higher plane

than the fork-tube-connecting ends a^2 , b^2 , or c^2 , with inclined intermediate portions a^3 , b^3 , or c^3 . Tube-inclosing sleeves d and e extend between the plates at the center and ends, 20 respectively, and the top plate a has upwardly-cupped ends a^2 , arranged in line with the sleeves e .

What I claim is—

The design for a crown for bicycle-forks 25 substantially as shown and described.

Signed by me at Reading, Pennsylvania, this 19th day of August, 1899.

WILLIAM F. REMPPIS.
